Inventor:

By his Attorney,

Hansen and Hansen

UNITED STATES PATENT OFFICE.

GILBERT W. GOODRIDGE, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ADAPTER.

Application filed May 27, 1918. Serial No. 236,698.

To all whom it may concern:

Be it known that I, GILBERT W. GOODRIDGE, a citizen of the United States of America, residing at Bridgeport, in the 5 county of Fairfield and State of Connecticut, have invented certain new and useful Improvements in Adapters, of which the following is a specification.

My invention relates to adapters and particularly to an adapter by which an Edison receptacle may be converted into an Edi-Swan receptacle, the object of my invention being to provide a simple and economical device for accomplishing this purpose.

15 In the accompanying drawing,

Fig. 1 is a broken side elevation of an adapter in which my invention is embodied in one form;

Fig. 2 is a cross section on the line 2—2, 20 Fig. 1;

Fig. 3 is a side elevation, partially in section, of a modified construction;

Fig. 4 is a drop perspective of the elements constituting the adapter shown in 25 Fig. 3.

In the construction shown in Fig. 1, the adapter comprises an insulating body 10 having at its entering end a projecting nose 11 and adjacent its outer end a flange 12. 30 Surrounding the body piece 10 is a screw shell 13, the flange 14 of which overlies the ledge 15 from which the nose piece 11 projects. The opposite end of the screw shell 13 is spun into an annular groove 16 adjacent the flange 12, thus holding the screw shell rigidly in position on the body 10 and preventing its endwise escape therefrom. A screw bolt 17, passing through the flange 14 and a hole in the body 10 of the receptacle, engages the tapped end 18 of the socket 19 in which works the plunger contact 20 forming one of the Edi-Swan spring terminals. On the nose 11 is mounted a center contact plate 21 held in position by 45 a screw bolt 22 which pierces the insulating body 10 and threads into a tapped hole in the angle strap 23. To the other end of the strap 23 is secured the socket 24 for the other spring plunger contact 25. The two 50 sockets 19 and 24 are located in a well 26 formed in the outer end of the insulating body 10, while the contacts 20 and 25 project beyond said end into position to engage the corresponding contacts of an inserted lamp base. A metallic shell 27 with

bayonet slots 28 is secured on the outer end of the body by crimping one end thereof into a channel 29 adjacent the flange 12, and is held against rotation by offsetting the shell inward at 30 and 31 into recesses 32 60 and 33 formed in the sides of the body 10. This shell is preferably threaded at 34 to receive a tapped ring 35, by means of which a shade or shade holder may be gripped between the ring and the flange 12 or the 65 body of the receptacle in which the adapter is inserted.

In Figs. 3 and 4 I have shown a modified construction in which the insulating body comprises a button 36 carrying the adapter 70 contacts 37 and 38 and the center contact 39 of the plug member of the adapter. The screw shell contact 40 of the adapter has a flange 41 which overlies the shoulder 42 of the button and engages the strap 43 when 75 drawn down hard against the button, thus establishing electrical connection between the screw shell and the adapter contact 38. The bayonet slot shell 44 has a broad thread 45 rolled therein, corresponding to the 80 thread of the screw shell 40, and has screwed thereon a similarly tapped collar 46 of insulation, such as fibre, paper, or the like. Both shell 44 and collar 46 are notched at 47, 48, respectively, to engage a lug 49 85 formed on the button 36 so as to hold these parts against relative rotation. In order to secure the several parts together, it is necessary merely to screw the threaded end 45 with its insulating collar 46 into the screw 90 shell 40. When screwed fully home, the shoulder 42 of the button 36 is halted by the flange 41 of the screw shell 40, which is now in engagement with the plate 43, thus establishing electrical connection with the 95 adapter contact 38.

Various modifications in detail of construction will readily occur to those skilled in the art which do not depart from what I claim as my invention.

I claim:—

1. An adapter comprising an insulating button having a boss projecting from the entering end thereof, a center contact on said boss, a connecting strap seated in the opposite end of said button, an axial connecting member engaging said center contact and strap to hold the same assembled on said button and to establish electrical connection therebetween, a contact stud mounted on 110

2
said strap and arranged out of alinement with said connecting member, together with a screw shell surrounding said button and having a flange overlying the entering end 5 of the button around said boss, a contact stud arranged on the opposite end of said button, and a connecting member passing through the button and serving to mechanically and electrically connect said screw shell and stud and to secure the same upon 10 said button, substantially as described.

2. An adapter comprising an insulating button having a stud at its entering end, a peripheral flange adjacent its outer end, 15 the portion of the button extending beyond said peripheral flange being recessed, together with a lamp-holding shell surrounding said extended end of the button, and

having one end thereof crimped into said recess adjacent the peripheral flange, substantially as described. 20

3. An adapter comprising an insulating button having a transversely elongated recess at its outer end, contact studs arranged at opposite ends of said recess, screw shell 25 and center contacts arranged at the entering end of the button, and means passing through the button and serving to electrically connect and mechanically secure the screw shell to one of said studs and the center contact to the other of said studs, substantially as described. 30

In testimony whereof I have signed my name to this specification.

GILBERT W. GOODRIDGE.
